CATHODE-RAY TUBE SYSTEM

Kurt Schlesinger, Berlin, Germany, assignor, by
mesne assignments, to Loewe Radio, Inc., a cor-
poration of New York

Application June 21, 1938, Serial No. 214,914
In Germany July 24, 1937

2 Claims. (Cl. 250—27)

To obtain the great intensity of light which is required by the luminous screen upon the projection of a television image potential of 10 to 20 kilovolts with ray currents of 1 to 2 milliamperes are necessary. For several reasons it appears desirable not to apply this high potential to the cathode ray system direct, but to connect the same only in the vicinity of the luminous screen. If the reverse method were adopted, the deflection of the electronic ray would be rendered much more difficult, as the electrons already possess a very considerable stiffness when leaving the final anode of the system. Moreover the problem of insulation causes difficulties in the design of the system.

The use of after-acceleration between anode and screen is very old. It was believed heretofore that it was necessary to perform this after-acceleration in a comparatively large number of stages, i. e. to allow the same to increase progressively. There have accordingly been set forth by other sources (Erich Schwartz: "Fernstehen und Tonfilm," Television and Sound Films, 1935, pages 37 to 40 and 47 to 49) after-acceleration systems, which were formed by resistance layers, and in which it was the object to attain a gradual increase in the speed of the electrons towards the luminous screen. According to Knoll the same effect was to be accomplished by a plurality of superimposed rings, between which there were applied external resistances. The disadvantage of all of these arrangements is the strong detrimental generation of heat, i. e. the great power dissipation of the "resistance accelerators." Experiments conducted by the applicant have shown that a gradual step-by-step acceleration of this kind is unnecessary. It is sufficient to apply the initial potential and the final potential each to an annular electrode, i. e. to design the system merely with two poles. Owing to the lack of any built-in resistances a tube of this kind remains perfectly cold in operation. The only difficulty occurring in these systems is the detrimental lens effect of the bipolar system. This lens effect acts in distorting fashion on the form of the picture, as the electronic ray is already deflected behind the system anode, the same leading to a barrel-shaped distortion of the form, as it increases towards the edge of the picture. The applicant has found that it is possible with prescribed form of picture to eliminate this lens effect entirely if the amount of the part-potential of the input-system, i. e. the fraction of the total potential that is applied to the annular electrode on the input

side, is selected to be sufficiently high. This intermediate value is critical and, as the applicant has found, may not in the case of the dimensions set forth below be less than one-third of 5 the screen potential.

As further difficulty associated with the after-acceleration it was found that if a dividing of 10 the potential was performed between the anode potential of the system and the potential of the luminous screen, the internal resistance of the potentiometer caused considerable variations in the anode potential dependent on the intensity of the ray current. This will be dealt with at a later point.

15 The invention is illustrated by the appending drawing of which—

Fig. 1 shows the diagram of a tube according to the invention and circuits connected therewith, whilst

20 Fig. 2 shows means for supplying electrodes of said tube with adapted voltages.

In Fig. 1 there is shown by way of explanation the assembly of a projection tube with division of the potential. In the most general instance the tube will possess in the vicinity of 25 the luminous screen 1 an annular electrode 2, which is connected with the point of maximum potential of the anode potential source 3. The tube system is represented diagrammatically

30 by the tube anode 4, the tubular member 5 which forms together with 4 a lens, the control electrode 6 and the cathode 7. The cathode 7 is connected with the negative pole of the potential source 3, and the control electrode 6 with the receiving apparatus 8. The deflecting elements, 35 represented by the deflecting plates 9 and 10, are situated behind the anode 4. They are connected with the potential of the anode 4 by way of the relaxation transformer 11, at the centre.

40 Since the screen electrode 2 has a much higher potential than the system formed by the anode and the deflecting plates, there must necessarily result between the two groups of electrodes a field line disposal having characteristics acting in de-focussing fashion on the ray. It is particularly adverse that these characteristics vary upon the deflection of the ray dependent on the position thereof, as during the 45 operation the ray assumes all spacial points of a pyramid, the base of which is represented by the luminous screen and the apex approximately by the centre of the plate. If this lens field is sufficiently strong and the ray is sufficiently soft after leaving the plates, considerable defor-

50 55

mations of the rectangular image accordingly result on the screen.

As first remedy the applicant experimented with the provision of a rotational-symmetric annular electrode. The annular electrode is designated 12 in Fig. 1 and is raised normally to the potential of the anode 4. It is assembled coaxially to the tube and the screen electrode and comprises a plate 12a with central opening and an annular fitting 12b. The openings in the two are in the ratio 1:2, and the height of the cylindrical fitting is such that the field, regarded from the screen, is cylindrical-symmetrical, so that the geometric form of the deflecting elements no longer affects the disposal of the field after leaving the annular element. As shown in practice, a height of the cylinder amounting to one-quarter of the diameter of the cylinder is sufficient for this purpose, so that the height of the cylinder, therefore, is approximately equal to the radius of the aperture in the cover 12a. If there is employed a system terminating means 12 of this kind in conjunction with a cylindrical wall coating 2, there is rendered possible in the first place the use of deflecting elements of desired form, for example plates or iron plate boxes, for mixed electrical and magnetic deflection, without interference with the circular form of the image point by the after-acceleration.

There now occurs, however, the following problem: If the component potential e_a is selected to be very low, there is certainly obtained a very great sensitivity of deflection, but a considerable distortion of the picture form. This usually makes itself noticeable as a barrel-shaped distortion, the four corners of the previously rectangular picture being forced towards the centre. The reason for this barrel-like distortion in the case of an anode part-potential which is too small is the increasing concentrating effect of the after-acceleration lens system comprising the electrodes 12 and 2 at the edge of the cross-section of the pyramid of deflection. If vice versa the anode potentiometer is displaced in the sense of increasing system anode potential, sensitivity of deflection is lost, the requirement for deflection power is very considerably increased, and the tube system is overloaded by excessive suctional or anode potentials and correspondingly increased biasses and also by insulation stress. The applicant has found that there is a most favourable value for the component potential of the anode 4 at which, with prescribed size of the picture, the error in the shape, i. e. the barrel-like distortion, just disappears. Excess beyond this value upwards is detrimental from the point of view of power for the reasons stated, whilst excess beyond this value downwards is prohibited by the distortion of the picture then occurring. A condition relative to the fact that an optimum adjustment of this nature exists at all is that the field behind the deflection is rotational-symmetric. The potentiometer value found is located almost exactly at one-third of the total potential 3, a deviation downwards, for the reasons stated, being more critical than a deviation upwards. According to the invention, the bias value of the control electrode 6, upon these adjustments, is always readjusted to constant current, whereby it is always possible to attain a constant light intensity of the screen.

As already mentioned above, a difficulty now occurs when using potentiometers 13 and 14 owing to the fact that if upon the control of the light intensity the ray current increases the existing po-

5 tentials in respect of the "no-load conditions" $i=0$ (black in the image) are not maintained, the potential values being shifted to a greater or smaller extent. It is clear that the absolute value of the resistance 14 is limited in the downward direction by the efficiency of the rectifier of the power supply apparatus supplying the anode potential 3. For example, with 20,000 volts it is hardly possible to pass a current of more than a few milliamperes through the potentiometer, as this current in any case is uselessly consumed and potentiometers for these high potentials become more and more ungainly and difficult to build with increasing output. A bridging of the potentiometer with condensers is also useless, as in television operation an enduring stationary light intensity of the image must always be reckoned with, in which connection a signal duration can always occur, which is greater than the time constant capable of being attained by the condensers.

10 The applicant, therefore, in the connection system shown in Fig. 2, has tried a circuit, which produces with a minimum of internal resistance the described critical ratio between main potential and component potential and at the same time dispenses entirely with a potentiometer with its trouble-some shunt current requirement. The special connection system in Fig. 2 is similar in its 15 design to the known potential-doubling system consisting of a transformer 15 and two rectifying tubes 16 and 17 connected to part-windings of the secondary, and differs from the same only insofar as the first tube utilises less than a half of the complete number of turns of the secondary. The condenser 13a is charged, for example, to 5,000 volts, and the condenser 14a to 10,000 volts, so that the ratio of 1:3 in respect of the anode 20 part-potential is supplied without variation. A special potentiometer is accordingly unnecessary, and the screen electrode 2 can be connected with the tube 17 directed by the anode 4 of the system 25 being connected with the lower-voltage tube 16. The size of the condensers 13a and 14a depends on the degree of steadyng and the energy requirement of the connected tube circuits. In the 30 case of a good-projection tube, in the ideal instance, the current to all intermediate electrodes should disappear, and the total current entering the cathode 7 should reappear at the screen or the screen ring 2. This ideal requirement is practically never capable of being attained with tubes having a high ray power of this nature. It can be accomplished, however, that the maximum 35 current loss amounting to approximately 50% leaks off practically entirely to the intermediate anode 4, and not previously to the elements: control electrode, tubular member, etc. It is accordingly to be expected that the ratio of the outputs 40 of screen circuit and anode circuit amounts to approximately 2:1, and the condenser 13a will accordingly be made at least twice as large as the condenser 14a. In practice values of .1-.2 mf. for the condenser 13a and .05 mf. for the condenser 14a have been found to be fully adequate upon 45 connection of a projection tube with a ray power of 30-40 w. The tube concerned had a cathode current of 2 milliamperes, of which approximately one-half reached the screen, and operated at 20 kilovolts screen potential with a potential distribution in the stated ratio of 1:3, i. e. with an anode part-potential of 6,500 volts at the system anode 4.

50 It is clear that in the case of differently dimensioned system assemblies, i. e. in the case of

other reciprocal conditions in the after-acceleration lens 12 and 2, other values may be necessary with respect to the component potential, which can be fulfilled simply by varying the tapping m at the transformer of the power supply apparatus. The important advantage of this divided potential-doubling connection, viz. the constancy of the potential amounts owing to the small internal resistance of the circuits and the possibility of managing with merely one transformer for the tube, is maintained also in the case of these variations.

It is to be observed that the edges of both the system cover 12b and the wall coating 2 must be completely rounded off by bending over or by the inclusion of circular wires in order to avoid the occurrence of corona discharges under the action of the considerable difference in potential between 2 and 12.

I claim:

1. In cathode ray apparatus, a cathode ray tube having included therein an electron emitting cathode, a first accelerating electrode, a target element, a second accelerating electrode closely adjacent the target, and electron beam deflecting means intermediate the accelerating electrodes, and auxiliary electrode means electrically connected with the first accelerating electrode and positioned intermediate the deflecting means and the second accelerating electrode, a source of energizing voltage for energizing said electrodes comprising a source of alternating current, a transformer having primary and secondary windings, said source of alternating current being connected across the primary winding, a connection from one terminal of the secondary winding to the first accelerating electrode, a first unidirectional conductor having one terminal connected to the other terminal of the secondary winding and the other terminal connected to the second accelerating electrode; a second unidirectional conductor having one terminal connected to a point on the transformer secondary winding intermediate the terminals thereof and its other terminal connected to the cathode of the cathode ray tube, a connection from said cathode to a point of fixed potential, a first con-

denser connected between the first and second accelerating electrodes and a second condenser connected between the first accelerating electrode and the cathode, said second condenser being of the order of at least twice the capacity of the first condenser, whereby a ratio of voltage between the auxiliary electrode and the second accelerating electrode of the order of two times that between the cathode and the first accelerating electrode is obtained.

2. In cathode ray apparatus, a cathode ray tube having included therein an electron emitting cathode, a first accelerating electrode, a target element, a second accelerating electrode closely adjacent the target, and electron beam deflecting means intermediate the accelerating electrodes, and auxiliary electrode means electrically connected with the first accelerating electrode and positioned intermediate the deflecting means and the second accelerating electrode, a source of energizing voltage for energizing said electrodes comprising a source of alternating current, a transformer having primary and secondary windings, said source of alternating current being connected across the primary winding, a connection from one terminal of the secondary winding to the first accelerating electrode, a first diode rectifier having its anode connected to the other terminal of the secondary winding and its cathode connected to the second accelerating electrode, a second diode rectifier having its cathode connected to a point on the transformer secondary winding intermediate the terminals thereof and its anode connected to the cathode of the cathode ray tube, a connection from said cathode to a point of fixed potential, a first condenser connected between the first and second accelerating electrodes and a second condenser connected between the first accelerating electrode and the cathode, said second condenser being of the order of at least twice the capacity of the first condenser, whereby a ratio of voltage between the auxiliary electrode and the second accelerating electrode of the order of two times that between the cathode and the first accelerating electrode is obtained.

KURT SCHLESINGER.
